UNITED STATES PATENT OFFICE

1,947,899

SHARPENER FOR SLICING MACHINES

William J. Campbell, Indianapolis, Ind., assignor
to American Slicing Machine Company, Chi-
cago, Ill., a corporation of New York

Application September 16, 1932
Serial No. 633,522

7 Claims. (Cl. 51—248)

My invention relates to an improvement in slicing machines and has for one purpose the provision of improved sharpening means for the knife. Another object is the provision of improved bearing means for the knife. Another object is the provision of improved means for assembling knife shaft and knife pulley. Other objects will appear from time to time in the course of the specification and claims.

10 The present application is a continuation in part of application No. 598,131, filed on March 11, 1932.

I illustrate my invention more or less diagrammatically in the accompanying drawings, where-
15 in—

Figure 1 is a front elevation;

Figure 2 is an end elevation with parts in sec-
tion; and

Figure 3 is a partial top plan view with parts
20 broken away.

Like parts are indicated by like symbols throughout the specification and drawings.

Referring to the drawings, A generally indicates any suitable base and anti-vibrational pads or
25 supports A¹ which rest upon any suitable supporting surface A², for example a counter or the like.

B indicates a motor housing mounted on the base A. B¹ is the motor shaft and B² a pulley
30 on the shaft about which passes any suitable belt B³.

C indicates a housing extension projecting upwardly from the base A. Formed integrally with it is a flared sleeve C¹ terminating rearwardly in
35 a generally cylindrical portion C². Positioned within the portion C² is a sleeve C³ which is provided with a screwthreaded aperture C⁴ adapted to receive the screwthreaded end of the oiling duct C⁵ which oiling duct is provided for example
40 with a hexagonal head portion C⁶ and an inlet cup C⁷. Note that the sleeve C¹ is apertured as at C⁸ to permit the passage therethrough of the screwthreaded portion C⁵. The aperture C⁸ is of substantially greater diameter than the screw-
45 threaded member C⁵, thus permitting of adjustment in the position of the sleeve C¹.

The forward face of the upstanding housing member C is closed as by the guard plate generally indicated as H. The axis of the knife G⁵ is
50 slightly tilted to permit the arcuate edge H¹ of the guard plate to penetrate the forward hollow G⁷ of the knife and to lie substantially flush with the very slightly bowed cutting plane defined by the cutting edge of the knife. The guard plate is
55 shown as carrying any suitable scraper H² the

details of which do not form part of the present invention. The lower edge of the guard plate is notched as at H³ H³ to seat upon supporting pins H⁴ which may be screwthreaded for adjustment. The upper edge of the guard plate is provided with inwardly extending ears H⁵, shown as at right angles to the face of the plate proper, such ears overlying top horizontal portions H⁶ of the frame member C. These ears are slotted as at H⁷ in such fashion that when the plate is in the position in which it is shown in Figure 3 they pass about the screwthreaded securing pins H⁸. These securing pins also serve to hold down the top of a cover plate H⁹ which cover plate is apertured as at H¹⁰ for a purpose later to appear. 60 65 70

In order to sharpen the knife I provide a knife assembly positioned beneath the cover H⁹ which includes a unitary lever J with an outer handle J¹ extending outwardly through the aperture H¹⁰. Mounted along the lever, and herein shown as 75 rotatable in relation thereto, are the stone J² and the metallic burr removing disc J³. Yielding means are employed, for example the spring J⁴, for keeping the sharpening lever in intermediate position with the stone and the metallic disc both out of contact with the knife edge. The operator may move the lever in either direction, against the pull of the spring J⁴. The cover plate H⁹, as will be clear from Figure 1, is upwardly offset to give space for the sharpening 80 assembly. The lever J is shown as pivotally supported concentrically with one of the securing members H⁸. Such member may be surrounded by an appropriate bearing sleeve J⁵.

In order to make sure that the spring J⁴ is 90 properly positioned and aligned to hold the two stones or grinding elements J² J³ in neutral position except when actively in use I provide an adjustable abutment member J¹⁰ slotted as at J¹¹, the securing screws J¹² passing through such 95 slot. At the factory the proper adjustment can be made, or in case of displacement of parts the adjustment can readily be made by the operator or service man when the machine is at the point of use. 100

Positioned to the rear of the cutting plane is any suitable slice receiving tray, normally fixed in position and indicated as K.

Positioned on the base, and forwardly of the knife, are the tracks L L¹, the outer track L¹ 105 being for example mounted on outwardly extending arms L². Movable along said tracks is a carriage member generally indicated as L³ which includes track engaging members L⁴ L⁵. Mounted on the carriage L³ is the work receiving 110

member which includes a main portion L^8 , and an angular portion L^7 . L^8 indicates a pusher plate having a handle L^9 . L^{10} indicates a guiding pin for such pusher plate and L^{11} a sleeve for the pusher plate, slidale along said pin.

M generally indicates a gauge plate which may be actuated in any suitable manner in order to vary the thickness of the slice. The details of the gauge plate do not of themselves form part of the present invention. I illustrate, however, a control handle M^1 which, by any suitable lever connection, may move the gauge plate M toward and away from the cutting plane.

It will be realized that whereas I have described and shown a practical and operative device, nevertheless many changes may be made in the size, shape, number and disposition of parts without departing from the spirit of my invention. I therefore wish my description and drawings to be taken as in a broad sense illustrative and diagrammatic rather than as limiting me to my specific showing.

The use and operation of my invention are as follows:

26. The structure herein described and shown forms a light, easily operated and efficient slicing machine of the manual feed type, in which the rotary knife G^5 is rotated at relatively high speed by electric motor means. The carriage L^3 , is manually moved across the face of and past the cutting edge of the knife G^5 . The slices, engaged by the gauge plate M , are received on the slice receiving member K .

35. It is extremely important, in a machine of this type, that the knife be kept very sharp. I provide easily operable and simple means for effecting the sharpening action. The operator first moves the lever J downwardly, referring to the position of the parts as shown in Figure 3, 40. to bring the grinder against the edge of the knife. He may then move the same lever upwardly, which withdraws the grinder from the knife and applies the metallic burr remover, to clear the burr from the edge of the knife. When 45. the operator releases the handle J^1 the spring J^4 draws the parts into neutral position with neither grinding nor burr removing member in contact with the edge. Note that a single set of securing screws serves the triple function 50. of holding the cover plate H^9 in position, of securing the top of the guard plate H , and of serving as a pivot for the lever J . The cover plate serves as an efficient housing and protection for the sharpening mechanism.

55. I claim:

1. In a slicing machine including a base, a knife mounted on said base, and means for rotating it, a frame portion extending upwardly from said base adjacent said knife, and sharpening means for the knife including a manual control lever pivoted adjacent the knife, sharpening members directly mounted on said lever and supported thereupon and positioned on opposite sides of the cutting edge of the knife, and yielding means tending normally to hold said lever in intermediate position, with one of said sharpening members positioned opposite to each side of the cutting edge of the knife but out of contact with the knife.

70. 2. In a slicing machine including a base, a knife mounted on said base, and means for rotating it, a frame portion extending upwardly from said base adjacent said knife, and sharpening means for the knife including a manual control lever pivoted adjacent the knife, sharp-

ening members mounted on said lever and positioned on opposite sides of the cutting edge of the knife, and yielding means tending normally to hold said lever in intermediate position, with one of said sharpening members positioned opposite to each side of the cutting edge of the knife, but out of contact with the knife, and a cover plate for said knife, said cover plate overlying the sharpening means and being apertured to permit the escape therethrough of one end of the lever, and means for securing the cover plate to the frame portion including a plurality of screws, one of said screws coinciding with the axis of rotation of the lever.

80. 3. In combination, a rotary knife, a base on which said knife is mounted, means for rotating said knife, a manual control sharpening lever movably supported upon said base, a plurality of sharpening elements directly positioned on said lever, and supported thereupon one opposed to each side of the cutting edge of the knife, means for normally maintaining said lever in neutral position with each of said sharpening elements out of contact with the opposed knife edge, and manually operable means for moving said lever in either direction from said neutral position.

85. 4. In combination, a rotary knife, a base on which said knife is mounted, means for rotating said knife, a manual control sharpening lever movably supported upon said base, a plurality of sharpening elements directly positioned on said lever, and supported thereupon one opposed to each side of the cutting edge of the knife, yielding means for normally maintaining said lever in neutral position with each of said sharpening elements out of contact with the opposed knife edge, and manually operable means for moving said lever in either direction from said neutral position.

90. 5. In combination, a rotary knife, a base on which said knife is mounted, means for rotating said knife, a sharpening lever pivotally supported upon said base, a plurality of sharpening elements positioned on said lever, one opposed to each side of the cutting edge of the knife, and means for normally maintaining said lever in neutral position, with each of said sharpening elements out of contact with the opposed knife edge, and a manually operable handle associated with said lever whereby said lever may be moved in either direction from said neutral position, said means including a coil spring one end of which is secured to said lever and another end to the base.

95. 6. In a slicing machine including a base, a knife mounted on said base, and means for rotating it, a frame portion extending upwardly from said base adjacent said knife, and sharpening means for the knife including a manual control lever pivoted adjacent the knife sharpening members directly mounted on said lever and supported thereupon and positioned on opposite sides of the cutting edge of the knife, and yielding means tending normally to hold said lever in intermediate position, with one of said sharpening means positioned opposite to each side of the cutting edge of the knife but out of contact with the knife, and means for adjusting the location of said yielding means.

100. 7. In a slicing machine including a base, a knife mounted on said base, and means for rotating it, sharpening means for the knife, including

a lever structure pivoted adjacent the cutting plane of the knife, said lever structure including a manual control handle unitary therewith, and sharpening means for the knife, mounted directly upon said lever structure, including a sharpening member extending downwardly in front of each

side of the knife, and yielding means adapted normally to hold said structure in intermediate position, with each sharpening member opposite to one side of the cutting edge of the knife but out of contact with the knife.
